JOHN W. WHITLOCK, OF RISING SUN, INDIANA.

VALVE MECHANISM FOR INTERNAL-COMBUSTION ENGINES.

1,084,514.

Specification of Letters Patent.

Patented Jan. 13, 1914.

Application filed September 25, 1912. Serial No. 722,339.

To all whom it may concern:

Be it known that I, JOHN W. WHITLOCK, citizen of the United States, residing at Rising Sun, in the county of Ohio and State of Indiana, have invented certain new and useful Improvements in Valve Mechanism for Internal-Combustion Engines, of which the following is a specification.

This invention relates to valve operating mechanisms for internal combustion engines.

The primary object of the invention is to provide means for positively opening and closing the valve of an engine of this character in proper timed relation with the movements of the piston.

A further object of the invention is to provide an operating mechanism in which lost motion occasioned by wear or by improper adjustment will be taken up by resilient means and in which rattling of the parts is avoided which occurs when springs are used to actuate the valves.

In the accompanying drawings forming a part of this specification: Figure 1 is a vertical section; Fig. 2 a vertical section showing a slightly modified form of frame construction; Fig. 3 an edge elevation of the cams and the mechanism to which the same are active removed from the crank case; Fig. 4 a detail view of the arm which actuates the valve of the engine; Fig. 5 a disassembled perspective of the cams and the rollers to which the same are active; Fig. 6 an edge elevation of the roller supporting mechanism shown in Fig. 2.

The present invention contemplates the provision of cam means for operating the engine valve, and while the drawings do not show the mechanism for operating the shaft on which the cams are positioned, it will be noted that any usual construction may be employed which will rotate the cam shaft in proper timed relation with the movement of the piston.

In the drawings 10 designates the cylinder of an internal combustion engine, the cylinder being provided with a port 11 which is closed by the valve 12. The stem 13 of the valve 12 is supported by the head 14 for reciprocatory movement and its threaded terminal 15 receives the sleeve 16 of the yoke 17. This yoke is provided with the transversely disposed spaced bars 18 and 19. A bracket 20 is secured to the head 14, said bracket pivotally supporting the arm 21 one terminal of which extends between the pins

18 and 19 of the yoke 16. Thus it will be noted that when movement is imparted to the arm, the same will cause the valve stem 13 to reciprocate, the valve either opening or closing consistent with the direction in which the rocker arm 21 is moved. In order to compensate for over-travel of the rocker arm, and to prevent rattling of the valve operating mechanism, the upper and lower faces of the rocker arm adjacent its free terminal are concaved and provided with flat springs, the flat spring 22 of the lower face being active to the transverse pin 18, and the spring 23 of the upper face being active to the transverse pin 19. The springs will thus compensate for movement of the rocker arm between the transverse pins 18 and 19, and exert pressure on the valve after seating.

In the form shown in Fig. 1 of the drawings the sleeve 32 is supported by the frame 33, said frame being disposed for vertical movement within the crank case, the body portion 44 of the frame being held from turning by the rib 45 or other suitable means which is formed integral with the wall 46 of the crank case, said rib being disposed between the plates 47 and 48 which constitute the frame, the lower terminal 49 of the frame extending through an opening 50 in the crank case to properly direct the frame in its vertical movement. The cam shaft 39 is disposed between the curved extensions 51 of the members 47 and 48, the cams, which are similar in construction to those shown in Fig. 1 of the drawing, being active to the rollers 52 and 53, the trunnions 54 of which are supported by the members 47 and 48, the rollers being disposed in spaced relation and at a point adjacent the curved portions of the plates. The roller 52, which is acted upon by one of the cams, consists of a single disk, the cams disposed on either side of the central cam 40 riding clear of said disk, said cams contacting with the spaced disks 55 which constitute the roller 53. In this manner, it will be noted that as the cam shaft is rotated the cams will alternately impart movement to the frame 43 which will cause the rod 27 to actuate the valve operating rocker arm. In this form the rod 27 is adjusted within the sleeves 28 and 32 in order to regulate its stroke. The crank case 24 is provided with an opening 25 in which is positioned a bearing 26 in the form shown in Fig. 1, said

bearing receiving the rod 27, the upper terminal 28 of which is received by the sleeve 29, said sleeve being pivotally connected with the end of the rocker arm remote from the yoke of the valve, the sleeve being internally threaded to receive the threaded portion 30 of the rod 27, the rod in this manner being adjustable with the sleeve. In the form shown in Fig. 1, the lower terminal of the rod extends through the bearing 26 the bore of which is enlarged at its base, the larger bore 31 receiving the sleeve 32 which is interiorly threaded to receive the threaded terminal 31 of the rod.

15 In the construction shown in Figs. 2 and 6 of the drawings, the lower terminal of the rod extends within the crank case 24 through the opening 25 and is pivotally connected with the long arm 33 of the bell crank 34. 20 This bell crank or frame consists of the long spaced arms 33 and the short spaced arms 35, the frame being pivotally supported at 36 within the portion 37 of the crank case, the member 37 being bolted, or otherwise secured, to said crank case. In this form the 25 rod 27 is provided intermediate its ends with a turn buckle by means of which the same may be adjusted, thus regulating the stroke of the rod. A roller 38 is rotatably supported between the long arms 33 of the bell-crank 34, the terminals of the arms 35 supporting a similar roller 35', both rollers being disposed in the path of movement of cams arranged on the shaft 39. These cams 30 are formed integral, the cam surfaces 40 being active to the roller 35' which is supported between the terminals of the short arms 35. The rollers 35' and 38 consist of disks 41, the roller 38 being provided with 35 one disk which contacts with the central cam, the other roller consisting of spaced disks which contact with the cams arranged on either side of the central cam, the roller riding over the cam which is active to the 40 same, the cam at intervals imparting movement to the roller to swing the bell crank 34 on its pivot. When the cam surfaces 40 assume a position to act upon the roller 35' the bell crank will be moved on its pivot to 45 pull the rod 27 downward, which movement will cause the terminal of the arm 21 which extends within the yoke of the valve stem to be lifted, closing the valve. When the cam shaft 39 is rotated to a position where 50 the cam 42 contacts with the roller 38 of the long arms 33, the bell crank will be actuated to elevate the rod 27, this upward movement of the rod causing the valve to open. It will be noted that the spring will 55 compensate for over-travel of the rocker arm and at the same time prevent rattling of the mechanism when the valve is operated.

Attention is called to the peculiar construction of the cam and the manner in 60 which the same operates the valve actuator-

ing mechanism, it being noted that the inner central roller lifts the valve as the same assumes its highest point the divided roller having descended to the lowest portion of the outside part of the cam. As the cam shaft 70 is rotated the divided roller rolls to the large diameter and the central roller rolls to the small diameter, thus closing the valve, it being noted that the divided roller follows the central roller without "back lash." 75 The double cams are positioned on either side of the central cam to keep the pressure between the cams and rollers central with respect to the frame which supports the rollers. It will be noted that this construction provides a valve operating mechanism without the use of springs, there being means provided for preventing rattling of the mechanism and for taking up lost motion, said means causing the operating 80 rod to exert pressure on the valve after the same has been seated.

The many advantages of a valve operating mechanism of this character will be clearly apparent, as it will be noted that the same provides means for effectually opening and closing the valve of the engine, means being provided for compensating for improper adjustment of the working parts or for any inaccuracy of the stroke of the 90 operating rod due to expansion or contraction. It will also be noted that the construction is such as may be easily and economically manufactured and that the various parts may be readily assembled. 95

Having described the invention, what I claim is:

1. A valve operating mechanism for internal combustion engines comprising an arm pivotally supported by the cylinder adjacent the engine valve, said valve being provided with a stem which extends beyond the engine casing, a sleeve threaded on said stem, a yoke supported by said sleeve, said yoke including transversely disposed spaced pins, said arm extending between said pins, resilient means positioned on the arm and disposed for contact with said transverse pins, and cam means for imparting movement to said arm. 105

2. A valve operating mechanism for internal combustion engines comprising an arm pivotally supported adjacent the valve of the engine, said valve being provided with a stem the terminal of which is threaded, a yoke receiving said stem, said yoke including transversely disposed members, said arm extending between said members, said arm being concaved on its upper and lower faces adjacent one of its terminals, a flat 110 spring secured to each of the faces of said arms, and cam means for imparting movement to said arm to actuate said valve stem. 120

3. A valve operating mechanism for gas engines comprising an arm pivotally sup- 125

ported adjacent the valve of the engine, a connection between said arm and the stem of said valve whereby when said arm is moved on its pivot movement will be imparted to said valve, a rod pivotally connected to the terminal of said arm remote from said valve, said rod being supported for reciprocatory movement by the crank case of the engine, its lower terminal extending within said crank case, a bell crank pivotally supported within the crank case, said bell crank consisting of two pairs of spaced arms, said rod being pivotally supported between the terminals of one pair of arms, a roller supported by each pair of arms, and cam means for actuating said rollers to rock said bell crank.

4. A valve operating mechanism for internal combustion engines comprising an arm pivotally supported by the engine casing, a valve supported for reciprocatory movement by the casing, the stem of said valve projecting beyond the casing, a yoke supported by said stem, said yoke including transversely disposed spaced members, one terminal of said arm extending between said spaced members, the upper and lower faces of the terminal of said arm being concaved, springs secured to said upper and lower faces and disposed to extend across the concaved portions of the same, and means for

imparting movement to said arm to reciprocate said valve stem.

5. A valve operating mechanism for gas engines comprising an arm pivotally supported adjacent the valve of the engine, a connection between said arm and the stem of said valve whereby movement of the arm will impart movement to the stem of the valve, a rod pivotally connected to the terminal of the arm remote from said valve, said rod being supported for reciprocatory movement by the crank case of the engine, a frame including spaced members connected to the terminal of the said rod and arranged within the crank case, rollers supported in spaced relation by said frame, the portion of the frame intermediate the rollers being curved, a guide supported by the crank case and disposed to extend between the members which constitute the frame, a cam shaft disposed between the rollers which are supported by the frame, and cams mounted on said shaft, said cams alternately engaging said rollers.

In testimony whereof I affix my signature in presence of two witnesses.

JOHN W. WHITLOCK. [L. S.]
